Primary Examiner — Mark Goodwin

(57) **CLAIM**

The ornamental design for a loader boom knee casting, as shown and described.

DESCRIPTION

FIG. 1 is a top perspective view of a loader boom knee casting showing our new design in use condition.

FIG. 2 is an enlarged top perspective view thereof.

FIG. 3 is a bottom perspective view thereof.

FIG. 4 is a top view thereof.

FIG. 5 is a left side view thereof.

FIG. 6 is a bottom view thereof.

FIG. 7 is a right side view thereof; and,

FIG. 8 is a rear end view thereof.

The broken line showing of a loader boom and an extra loader boom knee casting is included for the purpose of illustrating environmental structure and forms no part of the claimed design.
